FULLERING-BLOCK FOR ROCK-DRILL BITS.

1,312,283.

Specification of Letters Patent.

Patented Aug. 5, 1919.

Application filed July 24, 1917. Serial No. 182,448.

To all whom it may concern:

Be it known that I, ORRIN B. CAMP, a citizen of the United States, residing at Engelmire, in the county of Plumas and State of California, have invented new and useful Improvements in Fullering-Blocks for Rock-Drill Bits, of which the following is a specification.

The object of the present invention is to provide a device for swaging, sizing and fullering drill bits.

Means for sharpening Carr bits, used with drills, have heretofore comprised only a block for swaging the bit, a block for sizing it, and a die for forming the edge of the bit. In order to obtain sharp corners on the bit it has heretofore been necessary, with the tools at present on the market, first, to swage the bit between a pair of swaging blocks, then to size it between a pair of sizing blocks, and then to press the end of the bit against a die. But while this process would cause the edge of the bit to correspond in a certain degree with the form of the die, yet it would only do so to a limited extent at the corners of the bit. Consequently, it has been necessary to re-heat the bit and repeat the process until finally the die was provided with sharp corners at its biting or cutting edge.

The object of the present invention is to form the bit with sharp corners by drawing or fullering its corners.

In the present invention I use only two blocks; namely, an upper block and a lower block, not only for swaging and sizing, but also for fullering, that is, for drawing out the corners of the bit so as to provide the bit with a sharp edge along its whole length.

In the accompanying drawing, Figure 1 is a perspective view of my improved blocks; Fig. 2 is a plan view of the lower block; Fig. 3 is a bottom view of the upper block; Fig. 4 is a longitudinal section through the blocks; Figs. 5, 6, and 7 are transverse sections on the lines 5—5 6—6, and 7—7 of Fig. 2.

Referring to the drawing, 1 indicates an upper block, and 2 a lower block, of a pair of sizing, swaging and fullering blocks constructed in accordance with my invention. The lower block 2 has at one end a flat upper swaging surface 3 for the greater part of its depth, its rear end terminating in an upwardly and rearwardly sloping surface 4.

In one direction said upper surface extends to the end of the lower block, and in the other direction is limited by a vertical wall 6, and the upper surface 10 of the lower block behind said sloping surface 4 is flush with the top of said wall. In like manner the corresponding end of the upper block 1 has a swaging surface 7 which is flat and extends from an end of the block to a wall 8, said surface 7 extending at the rear into a sloping surface 9, which, in turn, extends into a flat surface 11 which is flush with the rear end of said wall 8. When the blocks are placed together there is thus formed between said surfaces 3 and 7 a cavity in which the end of the bit is received, said cavity being at the rear end tapering and constituting the swaging part of the block, that is to say, when a bit is placed between said portions of the upper and lower blocks, in a heated and therefore slightly plastic condition, and the upper block is pressed down upon the lower block, the result is to squeeze the bit downward and also to form a tapering end thereon, this being formed by the two surfaces 4 and 9, against which the end of the bit is squeezed.

The other ends of the upper and lower blocks 1, 2, constitute fullering portions. The lower block has at its left hand end, as seen in Figs. 1, 2, a flat portion 12, which is triangular in shape and is limited at the end of the block by a high wall 13 extending along the end of the block and on the right hand side by a sloping surface 14. In like manner the upper block is formed with the flat surface 16 and a sloping surface 17 limiting the flat surface on one side. On the other side of said flat surface 16 is a depression or mortise 18, in which the upper edge of the wall 13 fits. There is thus formed, when said upper and lower blocks are fitted together, a cavity which is tapering or beveled on its right hand side and the width of which varies according to its distance from the front end. After swaging the bit in the manner just above described, the bit is placed on the lower block until its right hand corner rests upon the sloping surface 14 and then the upper block is brought down on it, thereby fullering or drawing out the right hand corner or end of the edge of the bit. When this has been done it is turned over so that the same operation is performed on the other end of the bit. In

this manner the ends of the edge of the bit are fullered or drawn out.

Both the lower and upper blocks are formed with registering conical recesses, the lower block with a recess 19 and the upper block with a recess 20. These recesses lie immediately to the left of the walls 6 and 8 respectively, which walls therefore extend obliquely across the blocks. These recesses 10 constitute the sizing part of the block, and the bit is placed in said recesses and said blocks are pressed together in order to compress the corners to the correct gage to reduce the bit to the proper size to be afterward treated by the dolly in the die. The wall 13 is of great importance, for it fits in the mortise in the upper block and prevents the bit from slipping away from the sloping

surfaces 4, 9, which it tends to do by reason of its being pressed between said surfaces. 20

I claim:

Means for fullering a corner of a drill bit having two beveled cutting surfaces, comprising two blocks, each having a depressed, flat, swaging surface, one of said blocks 25 having a wall or stop, an inner side of which is at right angles to the swaging surface of the block and the other having a mortise into which the upper portion of the block fits tightly, said blocks also having surfaces sloping upwardly from said swaging surfaces at an acute angle, the longitudinal directions of said sloping surfaces making 30 an acute angle with said wall.

ORRIN B. CAMP.
